Specification for Design.

Patented May 17, 1921.

Application filed November 26, 1920. Serial No. 426,655. Term of patent 14 years.

To all whom it may concern:

Be it known that I, VICTOR LOUGHEED, a citizen of the United States, residing at Santa Barbara, in the county of Santa Barbara and State of California, have invented a new, original, and ornamental Design for Vehicle-Wheels, of which the following is a specification.

In the accompanying drawing, forming

part of this specification, Figures 1, 2, and 3 are, respectively, an outer face view, an inner face view, and a partial axial section of a wheel embodying the form which constitutes my new design.

I claim:

The ornamental design for a vehicle wheel as shown.

VICTOR LOUGHEED.
